SHOE SHINING BRACKET WITH ADJUSTABLE SHOE TREE

Horace J. Jackson, Columbus, Ohio

Application September 10, 1946, Serial No. 695,923

4 Claims. (Cl. 12—128.6)

1

The present invention relates to improvements in shoe-shining brackets with an adjustable shoe tree and has for an object to provide an improved shoe tree readily adjustable to all size shoes and a shoe tree that will retain its initial setting regardless of the torsional stresses exerted upon the adjusting element during the various phases of the shoe-shining operation.

Another object of the invention is to provide an improved shoe-shining bracket with an adjustable shoe tree that is very portable and takes up very little space.

A still further object of the invention is to provide an improved shoe-shining bracket with an adjustable shoe tree according to the present invention which is comparatively simple, exceptionally strong, highly efficient in its use and very economical in its manufacture.

A still further object of the invention is to provide a means for stretching and for rebuilding the counter of a shoe which has been caved in.

All of the foregoing and still further advantages of this invention will become more apparent from the study of the following specification, and in connection with the accompanying drawings wherein like characters of reference designate corresponding parts throughout the several views and wherein,

Figure 1 is a top plan view of the improved shoe-shining bracket with an adjustable shoe tree.

Figure 2 is a side elevation of the improved shoe-shining bracket with the slide in the closed position.

Figure 3 is a vertical section taken through lines 3—3 in Figure 2.

Figure 4 is a vertical section taken through lines 4—4 in Figure 2.

Referring more particularly to the drawings, a mounting clip 1 having curved lips 2 is secured to a wall or door or any hard surface by means of screws 3. A mounting bracket 4 having flanges 5 and support webs 8 carries one end of a rod 7 and is retained on the rod 7 by means of an Allen set screw 6. The other end of the rod 7 is curved downwardly and outwardly having a shoe shell 27 affixed thereto by means of an Allen set screw 28.

Mounted and slidably carried on the rod 7 is a slidable adjustment member 9 comprising a leg 10 having a boss 11 at its upper end and a foot 12 at its lower end. The boss 11 has a bore passing laterally therethrough. The axis of this bore is perpendicular to the leg 10. Mounted on top of the boss 11 is a lip 13 for receiving a rivet 14 to pivotally mount a clamp 15. The clamp 15

has several holes 16 along its sides. The clamp 15 when looked at from an end view has a U-shape such that the sides of the clamp 15 may fit over and engage the rod 7. A toggle link 17 having arms 18 and 19 is merely a piece of hard drawn wire bent in a U-shape. A closed portion 20 of the U passes through a hole 21 in the rod 7 while the open ends of the U-shaped member are bent inwardly a substantial distance forming 10 hooks 22 and 23 to engage the holes 16 in the clamp 15. It will be noted that the underneath portion of the rod 7 has a flat surface 24 running a substantial length of the straight run of said rod.

15 Also, on the foot side of the slidable adjustment member 9 there is a flat key 25 retained in place on the slidable adjustment member 9 by means of a drive screw 26, the purpose of this being to give strength to the slidable adjustment member 9 when in operation and to resist any circular rotation or twisting of said unit. The clamp 15 and the toggle link 17 form a toggle mechanism such that when the clamp 15 is pulled forward, as shown in solid lines in Fig. 2, such that the slidable adjustment member 9 is pushed in the direction of the mounting bracket 4 the toggle link 17 and the clamp 15 come in alignment to form a toggle lock. This toggle lock arrangement is believed to be particularly advantageous in that 20 the only way the setting of the slidable adjustment member 9 may be moved is by disaligning the toggle link 17 and the clamp 15. Once the toggle lock has been formed, as shown in solid lines in Fig. 2, with the toggle link 17 and the 25 clamp 15 in alignment and the key 25 abutting the flat surface 24 there is no chance of this unit losing its adjustment unless acted upon manually by the lifting of clamp 15.

In operation the unit functions as follows. The 30 mounting bracket 4 comprising the rod 7, the slidable adjustment member 9 and the shoe shell 27 is placed in the mounting clip 1 such that the lips 2 engage and retain the flanges 5 on the mounting bracket 4. The arms 18 and 19 of the 35 toggle link 17 are then disengaged from the holes 16 in the clamp 15 until the size of a shoe 29 to be placed on the bracket is determined.

The shoe 29 is then slipped over the shoe shell 27 end of the bracket such that the shoe shell 50 27 engages the inside upper part of the toe of the shoe 29. The slidable adjustment member 9 is then moved to a position such that the foot 12 abuts the counter of the shoe 29.

The clamp 15 is then placed down upon the 55 rod 7 such that the sides envelop the top portion

of the rod 7. The toggle link 17 is then allowed to fall upon the clamp 15, and at this time the setting of the arms 18 and 19 with the clamp 15 is determined. The clamp 15 is then raised by means of placing a finger under a hook 30 of the clamp 15. While the clamp 15 is in the vertical position, as shown in dotted lines in Fig. 2, the toggle link 17 is adjusted by engaging the hooks 22 and 23 in the holes 16 in the sides of the clamp 15. The clamp 15 is then forced down upon the rod 7, as shown in solid lines in Fig. 2, such that the toggle link 17 and the clamp 15 come in alignment, thus forming a toggle lock.

It will be noted that this toggle lock cannot be broken by torsional stresses set up in the shoe-shining operation because the toggle lock forms a positive lock which can be broken only by disalignment of the clamp 15 and the toggle link 17.

This invention is believed to be a definite improvement over the friction type shoe-shining bracket as the toggle lock affords a positive retention of the original setting, whereas a friction type shoe-shining bracket may lose its setting due to the torsional stresses exerted in the shoe-shining operation which may cock the slideable adjustment member 9 to either the left or right side of the center bar and thus reduce the area of contact leaving the device open to variations either forward or backward of the original setting.

Although a preferred embodiment of the present invention is as illustrated and described, it is to be understood that such changes in construction and in the combination and arrangement of parts may be resorted to which will fall within the scope of the invention as claimed.

What I claim is:

1. An improved shoe-shining bracket comprising a support, relatively movable shoe engaging members carried on said support, a lever fulcrumed upon and having a motion of translation with a moving member, and a link pivoted at one end to said fixed support and pivoted at its other end to said lever at a point spaced from its pivot.

2. An improved shoe-shining bracket as

claimed in claim 1 wherein the lever has spring flanges biased to an in-sprung position adapted to frictionally grip the sides of said support when the lever is lowered whereby to create a clamp for holding the movable member against motion.

3. An improved shoe-shining bracket as claimed in claim 1 characterized by the fact that an off-set curved portion at the free end of the lever is arranged to form a finger grip or hold for raising the lever.

4. An improved shoe-shining bracket comprising a support, a shoe toe member on the support, a shoe counter member slidably mounted on said support, a lever pivoted upon and having a motion of translation with said shoe counter member and having a series of perforations therein, means to raise and lower said lever, and a toggle link pivoted at one end to said support and having its other end selectively pivoted in one of said perforations, said lever having a curved portion adjacent its end which is pivoted to the support whereby when the lever is lowered to its final low position engaging the support a line connecting the two end pivots of said toggle link will extend below the pivotal axis of the lever.
